Primary Examiner—Wallace R. Burke*Assistant Examiner*—Lavone D. Tabor[57] **CLAIM**

The ornamental design for a combination bucket and stool, as shown and described.

DESCRIPTION

FIG. 1 is a perspective view of a combination bucket and stool showing my new design;

FIG. 2 is a top plan view thereof;

FIG. 3 is a side elevational view thereof;

FIG. 4 is a bottom plan view thereof;

FIG. 5 is a front elevational view thereof;

FIG. 6 is a rear elevational view thereof;

FIG. 7 is a perspective view of a second embodiment of FIG. 1;

FIG. 8 is a top plan view thereof;

FIG. 9 is a side elevational view thereof;

FIG. 10 is a bottom plan view thereof;

FIG. 11 is a front elevational view thereof; and,

FIG. 12 is a rear elevational view thereof.

FIG. 1

FIG. 2

FIG.3

FIG.4
